GILES C. FULLMER, OF BRIDGEPORT, CONNECTICUT, ASSIGNOR TO THE BRIDGEPORT METAL GOODS MANUFACTURING COMPANY, OF BRIDGEPORT, CONNECTICUT, A CORPORATION OF CONNECTICUT

PICK-UP CANDLE LIGHT

Application filed July 18, 1931. Serial No. 551,778.

This invention relates to new and useful improvements in portable electric lights and has particular relation to a portable electric light in the form of a candle.

An object of the invention is to provide an improved switching means in a light of the kind stated whereby a circuit will be closed through a battery and bulb on the light being raised off a support, or whereby the circuit to the bulb may be manually closed to remain closed while the light is on a support as well as when the light is raised off the support.

A further object is to provide a light as stated and including two switch elements either of which may be moved into engagement with a contact to close a circuit to a bulb, and one of which is adapted to be normally positioned to move into engagement with the contact on the light being raised off a supporting surface and the other of which may be manually moved into engagement with the contact irrespective of the position of the first.

Other objects and advantages will become apparent from a consideration of the following detailed description taken in connection with the accompanying drawing, wherein satisfactory embodiments of the invention are shown. However, it is to be understood that the invention is not limited to the details disclosed but includes all such variations and modifications as fall within the spirit of the invention and the scope of the appended claims to which claims reference may be had for a definition of the invention.

In the drawing:

Fig. 1 is a view showing a complete candle light in accordance with the present invention, the view being in side elevation and parts being broken away to show more clearly the circuit;

Fig. 2 is a bottom plan view of the light, a part of the base being broken away;

Fig. 3 is a sectional view substantially along the line 3—3 of Fig. 2;

Fig. 4 is a side elevational view of a portion of the automatic switch element;

Fig. 5 is an end view of the same;

Fig. 6 is a perspective view of the mounting for the parts shown in Fig. 4;

Fig. 7 is a view of the disc of insulation forming part of the base and showing both of the switch elements in inoperative position;

Fig. 8 is a detailed sectional view showing a slightly modified construction of automatic switch element; and

Fig. 9 is a view of the spring of Fig. 8.

Referring in detail to the drawing, the improved candle light includes a base 10, preferably hollow and formed of sheet metal as shown. This base includes a centrally depending threaded portion 11 having an annular flange 12 to which a disc 13 of insulating material is secured as by means of rivets 14 and 15. Threaded into the portion 11 of the base is a sheet metal casing 16 which at its upper end carries clips 17 adapted to secure a globe or glass 18 to the casing.

A bulb 19 is threaded into a socket 20 electrically connected with the casing 16 and the center contact of the bulb engages the central contact 21 of a battery 22 enclosed in the usual insulating covering 22a and located within the casing 16. The battery 22 is held in position with its contact 21 in engagement with the central contact of the bulb as by means of a flat spring 23 of conducting material secured to the upper end of a post 24 of insulating material as by means of a relatively long rivet 25 which rivet extends through the post and has its head 26 disposed at the under side of the disc 13, whereby to form a contact and also secure the post to the disc.

Since the head 26 of the rivet 25 is arranged centrally or substantially centrally of the disc 13, it will be apparent that there is no circuit between the bulb and battery until the space between the contact or rivet head 26 and the casing or base is bridged. According to the present invention, two switch elements are provided for bridging this space and one of these elements is adapted to be entirely manually operated while the other is adapted to be normally automatic in its operation and to close a circuit between the battery and bulb on the light being elevated off a supporting surface.

The manually operable switching element is indicated at 27 and comprises a lever-like member pivoted intermediate its ends on the rivet 14 and having a hand or finger portion 28 disposed at one side of the base so as to be easily accessible. This element 27 also includes a contact portion 29 having a slightly upturned edge 30, the purpose of which will later be set forth. Obviously, by operating 10 the hand portion 28 of the element 27, the said element may be turned on its pivot 14 to bring its contacting portion 29 into engagement with the contact 26. A circuit will then be closed from the battery to the bulb, and 15 through the casing 16 to the base 10, and through the rivet 14 to the element 27, and from that element through the rivet 25 and spring 23 back to the battery. The upturned edge 30 facilitates the sliding of the contact 20 or switch onto the contact 26.

The automatic switch element includes a base or mounting portion 31 pivoted to the disc 13 on the rivet 15, and having a pair of upstanding ears 32 and a pair of stop lugs 25 31a and 31b on its opposite side. The circuit closing member of the automatic switch includes a relatively elongated member 33 having a contacting portion 34 and having one end portion off-set and bent upon itself 30 to provide a spring arm 35. Further, this member 33 includes spaced ears 36 adapted to be received between the ears 32 of the mounting member 31 and when a pin 37 is passed through the respective pairs of ears, 35 it will be appreciated that the member 33 is pivoted to the mounting member 31 for movement in a vertical plane relative thereto and about a horizontally extending pivot 37.

40 When the automatic switching element is in place its normal position is such that its portion 34 is either in engagement with the contact 26 or in line with said contact. When the parts 31 and 33 are assembled, the spring 45 arm 35 is received between the body of the member 33 and the mounting member 31 and compressed so that it is constantly endeavoring to rock the member 33 about the pivot pin 37 in a direction to force the end portion 34 toward the central contact 26. However, when the light is resting on a support, the off-set 38 of the member 33, will engage the support and rock the member in a direction to take its portion 34 away from the contact 26 as shown in Fig. 1 and open 50 the circuit through the lamp. As soon as the light is elevated or lifted from the support, the spring arm 35 will act to rock the switch element 33 on its pivot 37 and have its portion 34 engage the central contact 26 and complete a circuit through the battery and bulb as shown in Fig. 3.

Since the mounting member or means 31 is pivoted on the rivet 15, the entire automatic switch element or means may be swung

from its position where its contacting portion 34 is in alignment with the contact 26 as shown in Figs. 2 and 3 to an inoperative position as shown in Fig. 7. It will therefore be noted that the automatic switch element has both a vertical and a horizontal switch element. Its turning movement about its pivotal mounting 15 is limited in opposite directions by the stop lugs 31a and 31b engaging the edge of the insulating disc 13. Further, attention is directed to the fact that the contacting portion 34 of the automatic switch element includes upwardly off-set portions 34a whereby the switch may readily slide onto the contact 26 and also the manually operable switch element 27 may be moved on its pivot 14 to have its upturned edge 30 engage the contacting portion 34 of the switch element 33 and rock the switch element on its pivot 37 and against the action of the spring arm 35 so as to permit the contacting portion 29 of the manual switch element to enter under the contacting portion 34 of the automatic switch element to close the circuit.

From the foregoing description, it will be clear that the manual switch element may be operated to close a circuit between the battery and bulb irrespective of the location of the light, and irrespective of whether or not the automatic switch element is in circuit closing position. Further, it will be apparent that the automatic switch element may be put out of commission by turning it on its vertical pivot which is the rivet 15, and that the circuit may be operated entirely by the manual switching element.

Referring to the modified form of the invention, the parts are all the same with the exception that the automatic switching element identified in Fig. 8 by the numeral 39, does not include a spring arm similar to the arm 35 of the switching element 33 of the first form of the invention. In lieu of the arm 35 a spring 40 is provided and this spring includes an arm 41 engaging the mounting member 31 and an arm 42 engaging the member 39 at one side of the pivot pin 37. Further, the spring 40 includes an eye 43, to receive the pivot pin 37 whereby the spring is secured in place. Obviously, the operation of the modified form of automatic switching element is the same as that previously described and further description is therefore believed unnecessary.

Having thus set forth the nature of my invention, what I claim is:

1. In a portable electric light, a bulb, a battery, a contact, a switch element adapted to automatically move to engage said contact and thereby close a circuit between the battery and bulb on the light being raised off a support, a manually operable switch element, and said manually operable switch element operable to engage and move the automatic

switch element from the contact and to itself engage the contact to close the circuit between the battery and bulb.

2. In a portable electric light, a base, an upright casing on the base, a battery in said casing, a bulb grounded on said casing and disposed at the upper end thereof and having its center contact in engagement with the center contact of the battery, said base including a portion of insulating material, a contact electrically connected with the battery casing and mounted in said portion of insulating material, a pair of switch elements mounted on and each electrically connected with the base and through the base to the casing, one of said switch elements adapted to be manually moved to engage said contact and close a circuit between the battery and bulb, and the other of said elements pivoted on a horizontal pivot to move and engage said contact to close the circuit on the light being raised off a support.

3. In a portable electric light, a base, an upright casing on the base, a battery in said casing, a bulb grounded on said casing and disposed at the upper end thereof and having its center contact in engagement with the center contact of the battery, said base including a portion of insulating material, a contact electrically connected with the battery and mounted in said portion of insulating material, a switch element mounted on and electrically connected with the base and through the base to the casing, said switch element including a mounting portion, a contacting portion pivoted on said mounting portion on a horizontal pivot whereby the contacting portion may move to engage said contact on the light being raised off a supporting surface, and said mounting portion arranged for turning movement on a vertical axis whereby the switch element may be moved to an inoperative position.

4. In a portable electric light, a base, an upright casing on the base, a battery in said casing, a bulb grounded on said casing and disposed at the upper end thereof and having its center contact in engagement with the center contact of the battery, said base including a portion of insulating material, a contact electrically connected with the battery and mounted in said portion of insulating material, a pair of switch elements mounted on and each electrically connected with the base and through the base to the casing, one of said switch elements adapted to be manually moved to engage said contact and close a circuit between the battery and bulb, the other of said switch elements adapted to move to engage said contact to close the circuit on the light being raised off a support, and the said other of said switch elements having an inclined portion and the manual switch element having a portion to engage said inclined portion to raise the said other

switch element off the contact to permit the manual switch element to move under the other switch element and engage the contact.

5. In a portable electric light, a base, an upright casing on said base, a battery in said casing, a bulb grounded on said casing and disposed at the upper end thereof and having its center contact in engagement with the center contact of the battery, said base including a portion of insulating material, a contact electrically connected with the battery and mounted in said portion of insulating material, a switch element mounted on and electrically connected with the base and through the base to the casing, said switch element including a mounting portion, said switch element comprising a contact member pivoted intermediate its ends to said mounting portion and having one end portion doubled upon itself and engaging the base and forming a spring normally tending to move the contact member toward the contact.

6. In a portable electric light, a base, an upright casing on said base, a battery in said casing, a bulb grounded on said casing and disposed at the upper end thereof and having its center contact in engagement with the center contact of the battery, said base including a portion of insulating material, a contact electrically connected with the battery and mounted on said portion of insulating material, a switch element mounted on and electrically connected with the base and through the base to the casing, said switch element including a mounting portion, a contact member mounted on said mounting portion by a horizontal pivot, and a spring disposed between the mounting portion and the contact member of the switch element and normally tending to rock the contact member of the switch element on its pivot to have the same engage said contact and close the circuit through the battery and bulb.

7. In a portable electric light, a base, an upright casing on the base, a contact on the base to engage a battery in the casing and including a conducting portion connected with the contact and exposed on the under side of the base, and a switch member grounded on the base and mounted to swing about a horizontal axis toward and from engagement with said exposed member and also mounted to swing about a vertical axis toward and from said member.

8. In a portable electric light, a base, an upright casing on the base, a contact on the base to engage a battery in the casing and including a conducting portion connected with the contact and exposed on the under side of the base, a mounting for a switch member grounded on the base and pivoted to turn about a vertical axis, a switch member mounted on said mounting to turn about a hori-

zontal axis to and from engagement with said exposed member and means on the switch member to engage a support when the base rests on said support to move the contact away from said exposed member.

9. In a portable electric light, a base, a casing on the base, a contact on the base, means to provide electrical connection from said contact to a battery in the casing, a switch member mounted to swing about a horizontal axis to and from engagement with said contact and having means to engage a support when the base rests thereon to move the switch member away from said contact, means to mount the switch member to swing about a vertical axis toward and from said contact, and manually operable means for operating said member about said vertical axis.

10. In a portable electric light, a base, a casing on the base, a contact on the base, means to provide electrical connection from said contact to a battery in the casing, a switch member mounted to swing about a horizontal axis to and from engagement with said contact, means tending to move the switch toward the contact, means to engage a support when the base rests thereon to move the switch away from the contact, a support for the switch mounted to shift said switch toward and from the contact, and manually operable means for shifting the support.

11. In a portable electric light, a base, a casing on the base, a contact on the base, means to provide electrical connection from said contact to a battery in the casing, a switch member mounted to swing about a horizontal axis toward and from said contact, resilient means tending to move the switch to engagement with the contact, means to engage a support when the base rests thereon to move the switch away from the contact, and a pivoted support for the switch adapted for manual operation to move the switch toward and from the contact.

12. In testimony whereof I affix my signature.

GILES C. FULLMER.
